[57] CLAIM

The ornamental design for a reconfigurable dinosaurian toy, substantially as shown and described.

DESCRIPTION

FIG. 1 is a front elevational view of a reconfigurable dinosaurian toy showing my new design in a humanoid configuration;

FIG. 2 is a rear elevational view;

FIG. 3 is a right elevational side view;

FIG. 4 is a left elevational side view;

FIG. 5 is a top plan view;

FIG. 6 is a bottom plan view;

FIG. 7 is a front side perspective view;

FIG. 8 is a front side perspective view of the toy being reconfigured into a dinosaurian configuration;

FIG. 9 is a bottom side perspective view of the toy being reconfigured into a dinosaurian toy;

FIG. 10 is a right side perspective view of the toy reconfigured into a dinosaurian toy;

FIG. 11 is a rear side perspective view of the embodiment of FIG. 10;

FIG. 12 is a front elevational view of the embodiment of FIG. 10;

FIG. 13 is a rear elevational view of the embodiment of FIG. 10;

FIG. 14 is a right elevational side view which is a mirror image of the left elevational side view of the embodiment of FIG. 10;

FIG. 15 is a top plan view of the embodiment of FIG. 10; and

FIG. 16 is a bottom plan view of the embodiment of FIG. 10.
